UNITED STATES PATENT OFFICE.

MADISON V. LEACH, OF MOUNT STERLING, KENTUCKY.

PAD FOR VEHICLE TOPS.

Application filed January 10, 1924. Serial No. 685,478.

The invention has for its object to provide a pad for the top or covering of vehicles which is complete in itself, that is, which includes the reinforcing web, the filler and the casing, and which may be supplied in an indeterminate length which may be rolled or folded and from which a required length may be cut, thereby saving time and cost, since the article may be manufactured and marketed as a trimming at a less cost than involved in preparing pads for vehicle tops in the accustomed way.

Other objects and advantages will be apparent and suggests themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:—

25 Figure 1 is a perspective view of a length of vehicle top pad embodying the invention,

Figure 2 is a plan view thereof, the parts being spread to show more clearly the reinforcement and the casing containing the 30 filler,

Figure 3 is an enlarged sectional view,

Figure 4 is a detail view showing the first step in the application of the pad to a bow of a vehicle top, and

35 Figure 5 is a view similar to Figure 4 showing the pad as it appears when attached to the bow.

Corresponding and like parts are referred to in the following description and designated in the several views of the drawings by like reference characters.

40 The pad comprises a casing 1, a filler 2 therein of cotton or other preferred material, a lining 3 and a reinforcement 4, the latter being stitched or otherwise attached to the lining and the casing 1 being attached along one edge to an edge of the lining and adapted to fold upon the latter, as indicated most clearly in Fig. 3. The reinforcement 4 consists of webbing and in the present instance includes two webs. However, it is to be understood that the number

of webs is immaterial and may be varied according to the nature of the work. The lining 3 and casing 1 preferably constitute parts of a single strip of fabric, an edge portion of which is folded to provide the casing and an edge portion of which constitutes the lining 3 which receives the reinforcement and upon which the casing containing the filler is adapted to fold. An edge portion of the strip is hemmed as indicated at 5, and the opposite edge portion is inturned as indicated at 6 and stitched through the inner side of the casing and the lining 3. Opposite edge portions of the casing 1 are stitched to provide a finish and maintain the shape of the casing.

45 A pad constructed in accordance with the present invention may be of indefinite length and formed into a roll or package from which any required length may be cut, or the pad may be provided in given lengths.

To use a pad of the present form, the casing and the lining are extended and are placed upon the bows 7 of the vehicle top, as shown most clearly in Figure 4, the lining and reinforcement being tacked to the bows in the usual way. The next step is to fold the casing over the reinforcement and lining, as shown most clearly in Figure 5, the free edge of the casing being tacked or otherwise secured to the bows.

50 What is claimed is:—

A vehicle top supporting pad formed of a piece of material folded on itself to provide three layers each of substantially the same width, the folds being on opposite sides and from opposite edges of the intermediate layer, the edges of the material being folded inwardly thereof and secured to the material adjacent the edge, filling secured between the intermediate and one of the outer layers and forming the pad, said intermediate and outer layers secured together on each side of the filling, and the other outer layer forming the lining for the pad and having reinforcements secured thereto, said lining being adapted to be folded away from the pad to be secured to the top support.

55 In testimony whereof I affix my signature.

MADISON V. LEACH.
